UNITED STATES PATENT OFFICE.

EDWIN N. LIGHTFOOT, OF NEW YORK, N. Y., ASSIGNOR TO THE CUTLER-HAMMER MFG. CO., OF MILWAUKEE, WISCONSIN, A CORPORATION OF WISCONSIN.

SHOE-BEADING MACHINE.

1,245,745.

Specification of Letters Patent.

Patented Nov. 6, 1917.

Application filed March 19, 1917. Serial No. 155,784.

To all whom it may concern:

Be it known that I, EDWIN N. LIGHTFOOT, a citizen of the United States, residing at New York, in the county of Bronx and State of New York, have invented new and useful Improvements in Shoe-Beading Machines, of which the following is a full, clear, concise, and exact description, reference being had to the accompanying drawing, forming a part of this specification.

This invention relates to shoe beading machines and more particularly to electrical heating thereof.

These machines are employed in the manufacture of shoes for applying the ornamental beading to the heel or other portion of the finished shoe, the application of heat to the beading roll being essential to proper functioning thereof.

Machines of this character have heretofore been heated by means of an open gas flame applied at or near the beading roll.

This method, however, is dangerous, inefficient and irregular in its action. The practically continuous pressure of inflammable or explosive gases in the air of shoe factories renders the use of an open flame exceedingly unsafe; while such flame is very easily extinguished or deflected from its proper position by relatively slight air currents, and the soot produced by the flame is likely to soil and damage the work. It has also been proposed to heat such machines electrically but it is understood that no economical and convenient means have heretofore been proposed for so heating the machines.

The present invention has among its objects the provision of safe, economical and efficient heating of machines of the character stated.

A further object is to incorporate an electrical heating element in a machine of the character stated in such relation as in no wise to interfere with the use of such machine and to be readily attachable thereto and detachable therefrom.

Other objects and advantages will hereinafter appear.

In the accompanying drawing, wherein is illustrated an embodiment of the invention,

Figure 1 is a perspective view showing certain essential elements of the beading machine together with the heating means therefor; and

Figs. 2 and 3 are enlarged detail views of the heating element.

Referring to the drawing, the beading machine illustrated comprises in general a pedestal 1, a beading roll 2 mounted upon a 60 rotatable shaft (not shown) which has a suitable bearing 3 at the top of the pedestal, a casting 4 surrounding said shaft between the roll and pedestal and a work abutting plate 5 secured at the top of the pedestal adjacent the roll and casting. The beading roll 2 is secured upon the shaft by means of a screw retained plate 6, the shaft being power driven by means of a belt 7 passing over a pulley 8 fast upon said shaft. The roll 2, however, is free for rotary slippage upon the shaft and while tending to rotate therewith the same is subject to restraint through engagement with the work. The casting 4 which provides a bearing for the 75 usual work holding strap, is secured to the pedestal 1 by being clamped about a reduced lateral extension of the bearing 3 by means of a clamping screw 9.

In the use of the machine, for example, 80 in applying a bead to the heel of a shoe, the shoe is held with its heel base firmly abutting the plate 5 and within the usual strap supported by the bearing casting 4. The heel edge to be beaded is thus brought in contact with the milled edge of the beading roll 2, the shoe being progressively rotated and shifted with respect thereto to insure proper application of the bead without abrasion, it having been found in practice 90 that heating of the roll insures permanency of the indentations and materially lessens the tendency to cut or scratch the work.

Referring to the heating means for the roll, the same includes a heating element 10 secured to the strap bearing casting 4 with which the said roll is in intimate contact whereby the necessary heat is conducted to the roll. For this purpose said casting is provided with a downwardly and backwardly projecting portion 11 forming with the main body of the casting an extended flat surface 12 to which the correspondingly shaped heating element 10 is intimately secured by means of screws 13. Thus the side 95 edge of the heating element 10 extends for some distance in close proximity to the rear face of the beading roll near its periphery, whereby heat is conveyed directly to the portion of the roll which particularly requires 100 heating.

The heating element 10 comprises a pair of flat elongated heating units 14, 15 welded or otherwise secured to the lower face of a

flat rectangular piece 16 of steel or other suitable material. The heating units 14, 15 are substantially of the character disclosed and claimed in Patent No. 1,150,426, granted 5 August 17, 1915 to W. S. Hadaway, Jr., having at their contiguous ends suitable screw terminals 17, 18 the opposite ends of said units being electrically connected to provide a continuous circuit therethrough. 10 Current is supplied to the heating element by means of suitable conductors 19, 20 connected with the terminals 17, 18.

By the above construction the inherent defects and dangers of the open gas flame 15 are eliminated; furthermore by the use of the flat type heater intimately engaging the correspondingly shaped strap bearing casting from below, the highest heating efficiency and current conservation are obtained. 20

The heater parts, moreover, and particularly the terminals, are completely protected against injury and in no wise interfere with the regular operation of the machine.

25 What I claim as new and desire to secure by Letters Patent is:

1. In combination, a pedestal, a beading roll revolvably supported thereby in a spaced relation thereto and an electrical heating element supported between said pedestal and said roll and in close proximity to the latter. 30

2. In combination, a pedestal, a beading roll having a shaft revolvably supported by said pedestal and heating means for said roll 35 including a heat conducting mass adjacent to said roll and said shaft and a flat type electrical heating element disposed substantially perpendicularly and in close proximity to the rear face of said roll.

40 3. In a shoe machine, in combination, a pedestal, a beading roll revolvably mounted thereon, a work-bearing member fixed to said pedestal in a projecting relation thereto and in close proximity to the inner face of 45 said roll and an electrical heating element

fixed to the under side of said member adjacent to the inner face of said roll.

4. In combination, a pedestal, a shaft revolvably mounted thereon and projecting therefrom, a beading roll on said shaft, a work-bearing member surrounding said shaft and fixed in an offset relation to said pedestal and in close proximity to said roll, said member having a flat under face and an electrical heating element of a flat type fixed to said face of said member in intimate contact therewith. 55

5. In a shoe machine, in combination, a pedestal, a shaft revolvably mounted thereon and projecting therefrom, a beading roll on 60 said shaft, a work-bearing member surrounding said shaft and fixed in an offset relation to said pedestal and in close proximity to said roll, said member having a downwardly and rearwardly projecting extension providing a flat under face, and a flat type electrical heating element fixed to said face of said member in intimate contact therewith, the edge of said heating element extending close to the rear face of said roll. 65

6. In a shoe machine, in combination, a pedestal, a shaft projecting therefrom, a beading roll on said shaft in spaced relation to said pedestal and revolvable with respect thereto, a work-bearing member surrounding said shaft between said pedestal and said roll, said member having a plane under face substantially parallel to the axis of said shaft and substantially perpendicular to the plane of said roll and in close proximity to the latter, and a flat type electrical heating element intimately secured to said face of said member for heating the same and the adjacent roll. 75 80

In witness whereof, I have hereunto subscribed my name. 85

EDWIN N. LIGHTFOOT.
